GAS LOCKS

Willard L. Morrison, Lake Forest, Ill., assignor to Liquefreeze Company, Inc., New York, N.Y., a corporation of New York

Filed June 1, 1960, Ser. No. 33,204

5 Claims. (Cl. 34—242)

My invention relates to improvements in gas locks and has for one object to provide a gas lock for cooling chambers and the like through which solid objects may pass while inhibiting flow of gas therethrough. Such a lock is especially applicable to a cold chamber wherein food-stuffs and the like are cooled by contact with cold gas and cold liquid such as gaseous and liquid nitrogen at substantially atmospheric pressure and temperatures in the order of —320 degrees F. The importance of the gas lock is that it makes it possible to prevent or at least to inhibit escape of the gaseous nitrogen and contamination of the gaseous nitrogen by atmospheric air. This is especially important when as in the preferred form of such operation the liquid is used as a bath in which the material to be frozen is immersed with resultant boiling of the gas and the gas boiled off is at substantially bath temperature and substantially atmospheric pressure withdrawn, reliquefied and returned for reuse. Under these circumstances, loss of gas or pollution by air is highly undesirable.

I propose to use a brush or brushes, the bristles of which close entry and exit ports but may be pressed aside while maintaining contact with food bodies to permit entry and exit of food bodies into and out of the cooling chamber. The brushes may be at rest or may rotate. A single brush may be used or a plurality of brushes in opposition to one another may be used. The brushes may be made of bristles, synthetic or natural, fur fibers or even flaps of woven material. Because the brush is flexible whatever kind of bristles are used, it furnishes a barrier or curtain inhibiting gas flow without effectively impeding movement of solids which merely pass the brush, bending the bristles aside while the bristles still maintain gas flow inhibiting contact with the solids.

If the brushes rotate they may under some circumstances be more effective as a gas flow barrier and also may offer somewhat less resistance to passage of solids through the bristle area but stationary or movable or alone or in opposition to other brushes, the bristles form a barrier which if it does not completely prevent gas flow, inhibits it to minimize mixture of ambient air with the cooling gas.

I propose under some circumstances to use a gas lock chamber open at one end to ambient atmosphere and at the other end to the cooling chamber. The gas pressure in the cooling chamber will be little if any above atmospheric, thus inhibiting tendency of entrance of ambient air to dilute the cooling gas. Each open end of the chamber will be closed by a brush or brushes. If the brushes rotate they will be rotated in opposite directions and will be masked by shrouds with a clearance between the shroud and the floor along which the solids travel, being just enough to permit the solid to pass along the floor through the brush. The shrouding will, as the brushes rotate, limit the area through which solids may move to an area but little greater than the area required for passage of the objects. If the brushes operate in opposite directions, under these circumstances they tend to force air or gas outwardly from the lock chamber toward atmosphere on one end and toward the cooling gas at the other, and under these circumstances tend to draw a vacuum in the area between the brushes.

I have illustrated my invention as applied to a food freezing apparatus but the gas lock is equally applicable to many other purposes.

2

My invention is illustrated more or less diagrammatically in the accompanying drawings, wherein

FIGURE 1 is a vertical section through the apparatus;

FIGURE 2 is a section along the line 2—2 of FIG-

URE 1;

FIGURE 3 is a detail section on an enlarged scale similar to a part of FIGURE 1;

FIGURE 4 is a section along the line 4—4 of FIG-URE 3 in the absence of the food package;

FIGURE 5 is a section similar to FIGURE 4 showing a food package passing through;

FIGURE 6 is a side elevation similar to FIGURE 3 showing a food package about to enter;

FIGURE 7 is a similar view showing the food pack- age about to leave in contact with the brush;

FIGURE 8 is a detailed section similar to FIGURE 1 showing a modified form;

FIGURE 9 is a section of a modified form along the line 9—9 of FIGURE 10;

FIGURE 10 is a section along the line 10—10 of FIGURE 9;

FIGURE 11 is a view into a modified form of the brush arrangement;

FIGURE 12 is a section along the line 12—12 of FIGURE 11.

Like parts are indicated by like numerals throughout the specification and drawings.

The housing 1 is adapted to contain a liquid nitrogen bath 2 and immediately above the bath in direct open communication therewith a gas chamber 3. Liquid nitrogen may be supplied to the bath through the duct 4. Gas evaporated from the bath may be discharged through the duct 5 and there may be interposed between the ducts 4 and 5 a nitrogen reliquefaction plant or as the case may be, liquid nitrogen may be supplied from any suitable source through the duct 4 and the gas wasted through duct 5 though in the interest of economy the gas will normally be reliquefied as it is evaporated by the foodstuff, being immersed in the bath.

Extending laterally from each side of the housing 1 are tunnels 6 and 7. Each tunnel defines a gas lock, the purpose of which as will hereinafter appear is to prevent escape of gaseous nitrogen from the gas chamber and to prevent entrance of ambient air thereto. As a general proposition, there will normally be maintained a pressure in the gas chamber of a fraction of an inch of water, enough to inhibit air entrance. The tunnels 5 and 6 define entrance and exit air locks. The operation of each air lock is the same and a description of one air lock will suffice for both.

The air lock has a flexible insulating floor 8 above which are outer and inner barrier brushes 9 and 10, the brushes being driven by any suitable means, for example, motors 11 which may be variable speed. Normally the brushes will be driven in unison in opposite directions so that the brush 9 between the gas lock and the outer atmosphere tends to urge gas outwardly from the lock to atmosphere and brush 10 between the gas lock and the cooling chamber tends to urge gas outwardly from the gas lock to the cooling chamber. Each of the brushes comprise central brush bodies 12, 13 with closely spaced, fairly soft bristles 14, 15 which may be of fiber or hair or fur or other material which will not become stiff and brittle in the presence of cold. These brushes are so disposed that they contact at all times the floor of the gas lock and the two brushes define between them the lock chamber 16. The floor 8 may be upwardly adjusted by hand wheels 17 and 18 in opposition respectively to the bristles 14, 15 to insure close contact with the bristles as they rotate because it is these bristles that are relied upon to furnish the closure of the barrier between the lock chamber 16 and the ambi-

ent air on the one hand and the cooling chamber on the other. The bristles being rotated at high speed are held against the floor 8 as by centrifugal force and their stiffness. Shrouds 19, 20 are associated with the brushes 9 and 10 and mask a substantial part of the periphery of each brush. The shrouds terminate enough short of the floor to just permit passage of the maximum size of food solid along the floor through the brush. The shrouds 19 and 20 limit gas flow and gas contact with the bristles to the narrow area between the floor and the brush along which the foodstuff travels, so that the brushes tend to so to speak brush the air or gas along the floor in response to the direction of rotary movement of the brush.

Food packages 22 may be pushed along the floor 8 mechanically or hand manipulated as the case may be. They pass beneath the brush 9 into the chamber 16 and then beneath the brush 10 into the cooling gas chamber 3, where they pass over the pulley 23 and engage the belt 24 which moves in the direction of the arrows. The belt 24 passes over the pulleys 29, 30, 23 and the larger diameter portion of the pulleys 27, 28. The belt 25 passes over the pulley 27a and the smaller diameters of the pulleys 27 and 28 and carry the food package gripped between them downwardly below the level of the liquid, thus insuring a complete immersion of each food package in the nitrogen bath.

The pulleys 27 and 28 as indicated in FIGURES 1 and 2 are of different diameters. The belt 24 is narrower than the belt 25. The belt 25 engages the smaller diameter of the pulleys. The belt 24 engages the larger diameters of the pulleys so the belts travel at slightly different speed as a result of the different diameters of the pulleys but the pressure of the belts on the food packages is so slight that they are propelled through the bath without difficulty.

As the food packages pass between the pulleys 29 and 27a they are discharged upon the floor 8 to enter the exit or discharge chamber where exactly the same situation prevailed as prevailed in connection with the entrance chamber.

Referring to FIGURES 3, 6 and 7, it will be noted in FIGURE 6, the food package 22 is just contacting the rapidly rotating brush. Since the package is thinner than the length of the bristles, it interferes with contact between the brush and the floor 8 only in a portion of the brush as indicated in FIGURE 5. Normally when there is no package present, the contact is clear across the brush as in FIGURE 4. As the brush contacts the package 22 in FIGURE 6, the bristles are displaced as shown but no opening is left for the air, the brushes, as a result of their stiffness and centrifugal force maintaining contact with the package and inhibiting gas escape. This continues as the package leaves the brush in FIGURE 7, the bristles tending to spring down behind the package to contact the floor.

In the modified form shown in FIGURE 8, two opposed pairs of brushes 32, 33 and 34, 35 are substituted for the single brushes. Otherwise, the operation is substantially the same except that under these circumstances it may be necessary to have brushes 36, 37 on either side of the lock to contact the sides of the food package.

The previous disclosure applies to a situation where the package is closed but if an open package or rather an open pan is to be used, the brushes from above must be omitted because they would brush the contents out of the pan. Under these circumstances, the modified form disclosed in FIGURES 11 and 12 is used. In this case, the pan travels along the floor 38 over a brush 39 onto the floor 40 over a brush 41 onto a floor 42. The upper portion of the pan is held by the brushes upwardly against the ceiling or roof 43. The clearance between the floor and the roof in this case is approximately the depth of the pan, there being sufficient clearance so that the pan will not bind but the clearance must be so slight

that as the pan is lifted from the floor and squeezed against the roof by the brushes, no spilling will occur.

Under these circumstances, the brush accomplishes exactly the same purpose as it does in the cases where the brush is above or on the side because the sole purpose of the brush is to furnish a barrier which will inhibit gas flow into or out of the lock chamber.

Under ordinary conditions, the rotational speed of any of the brushes will be relied on in part to maintain a snug contact with the floor or ceiling as the case may be and with the package as it passes through. The stiffness of the brush also contributes to maintaining this contact and under some circumstances, the brush might actually be at rest and still furnish an adequate barrier.

Under some circumstances also the brush bristles might be metallic subject to magnetization and the floor or surface along which the pan travels would be magnetized so that the brush bristles would be held against it by magnetic force. This would be especially appropriate in connection with a brush at rest or being used as the barrier.

I have shown, to illustrate my invention, a complete assembly of cold gas chamber, freezing bath and conveying mechanism. If solid food particles are to be frozen, they may be safely contacted by the bristle brushes as the pressures are so small as not to be harmful. However, if it is desired to cool soft cooked food in pans, such food cannot be contacted by the bristles and therefore I have disclosed an important modification where the pans are above rather than below the bristles and the pan with its open top slides along the floor, being pressed upwardly against the roof of the chamber.

I have used the term "bristle" broadly as covering any flexible element, be it woven flaps, synthetic bristles, fibers, threads, cords or the like. If flaps are used, they might extend clear across the brush or might be cut in strips or might be slit in conformity to the width of the package.

I have used the term "floor" broadly. It might be the bottom, the top or side wall but so long as it is something along which the food package travels, it is the floor which is in opposition to the brush or brushes. The floor may be continuous or discontinuous. A conveyor may pass along the floor, the brush sealing the conveyor as well as the food package or the food packages may be propelled from an outside source. The essential element is that the food package no matter how constituted, whether it goes through separately or in train is continuously sealed by the flexible sealing means so that the flexible sealing means, preferably a brush, inhibits gas flow along the bath followed by the food body.

Because the gas lock is continuously operative and is opened and closed merely by the passage of the food body therethrough, no complicated timing mechanism is needed. When a food body is presented to the gas lock, it opens the lock, passes through without substantial gas flow and closes after the food body without substantial gas movement. As a result material may go through the system making its own time.

The arrangement shown in FIGURES 1, 8 and 12 showing rotating brushes at opposite ends of the gas lock chamber discloses an arrangement where the rotation of the brush in opposite directions tends to draw a vacuum in the chamber by urging gas flow from the chamber toward atmosphere and toward the cold chamber, thus inhibiting loss of cold gas contamination of the cold gas by air. The rotation of the brushes thus simultaneously permitting contact of the bristles with the opposite wall of the chamber and with the object passed through and at the same time to some extent displacing gas.

If the brushes do not rotate no such vacuum occurs and under these circumstances only the stiffness of the bristle without the centrifugal effect or the stiffness of the bristles with the magnetic effect is relied upon to hold the bristles across the opening to make a gas inhibiting curtain. If

the brush is not rotated the dimensions of the brush can well be increased and the area occupied by the bristles may be varied depending upon circumstances. Only a slight thickness of bristles might be sufficient. On the other hand, the bristles might extend quite a long distance along the path of the object and in some circumstances only a single brush of greater or less width will be sufficient to inhibit gas flow.

I claim:

1. A gas lock including a chamber open at both ends having a smooth floor along which solid objects may travel into, through and be discharged from the chamber, a rotating brush closing each end of the chamber, the bristles thereof being in contact at their free ends with said floor and being free to yield to permit passage of solid objects along the floor while maintaining sealing contact therewith.

2. A gas lock including a chamber open at both ends having a smooth floor along which solid objects may travel into, through and be discharged from the chamber, a rotating brush closing each end of the chamber, the bristles thereof being in contact at their free ends with said floor and being free to yield to permit passage of solid objects along the floor while maintaining sealing contact therewith, the brushes rotating in opposite directions.

3. A gas lock including a chamber open at both ends having a smooth floor along which solid objects may travel into, through and be discharged from the chamber, a rotating brush closing each end of the chamber, the bristles thereof being in contact at their free ends with said floor and being free to yield to permit passage of solid objects along the floor while maintaining sealing contact therewith a shroud for each brush.

4. A gas lock including a chamber open at both ends having a smooth floor along which solid objects may

5 travel into, through and be discharged from the chamber, a rotating brush closing each end of the chamber, the bristles thereof being in contact at their free ends with said floor and being free to yield to permit passage of solid objects along the floor while maintaining sealing contact therewith, a shroud for each brush, the shroud terminating above the floor a distance sufficient to permit unimpeded passage of solid objects.

10 5. A gas lock including a chamber open at both ends only, a floor along which solid objects may travel into, through and be discharged from the chamber, the brush bristles being in contact with the floor and being free to yield to permit passage of solid objects along the floor while maintaining sealing contact therewith, means for 15 rotating the brushes in opposite directions whereby the bristles as they contact a solid object traveling along the floor move against such direction of travel at the intake end and with the direction of travel at the discharge end of the chamber, shrouds within the chamber masking the 20 brushes, there being clearance between the ends of the shrouds and the floor sufficient to permit passage of the solid objects.
